UNITED STATES PATENT OFFICE.

JAMES P. HOOPER, OF BALTIMORE, MARYLAND.

GUN-SLING.

1,210,475.

Specification of Letters Patent.

Patented Jan. 2, 1917.

Application filed September 27, 1915. Serial No. 52,812.

To all whom it may concern:

Be it known that I, JAMES P. HOOPER, a citizen of the United States, residing at Baltimore, in the State of Maryland, have invented certain new and useful Improvements in Gun-Slings, of which the following is a specification.

This invention relates to improvements in gun slings and has particular reference to an improved sling and the manner of attaching the same to a gun whereby the sling may be drawn taut or elongated to form a loop without the use of buckles or tongues to penetrate the strap of which the sling is formed.

The object of the invention is to provide an improved arrangement of gun sling which latter is formed of a flexible strap preferably of woven webbing and to provide an improved mode of attaching the sling strap to the spaced apart fixed links one of which is usually provided on the barrel and the other on the stock of the gun, so that without disturbing the relation of the two links with respect to each other, the stretches of webbing between the two fixed links may be lengthened to produce a loop therein, or shortened to draw the same taut, and to effect this adjustment without perforating the webbing to receive a buckle tongue or providing a toothed buckle to penetrate such webbing, both of which means would more or less weaken the sling. With these, and other objects in view, the invention is illustrated in the accompanying drawing, wherein,—

Figure 1, shows a gun in side elevation, to which my improved sling is attached. Fig. 2, illustrates the same in inverted or bottom plan. Fig. 3, also shows the gun and illustrates the attached sling adjusted to form a loop whereby to enable the gun to be slung over the shoulder. Fig. 4, shows a face view of a grip frame which is pivotally attached to one end of the sling web. Fig. 5, illustrates the same in edge view. Fig. 6, shows an edge view of a hook device that is attached to the other end of the sling web, and Fig. 7, illustrates the flat side or face of the same.

Referring to the drawing the numeral 8, designates the stock of a gun; 9, the barrel thereof; 10 a link pivotally attached to the under side of the stock and 11, a pivoted link carried by a clip 12, that embraces the

barrel. The links 10 and 11 respectively may be attached to the gun at points somewhat different from that shown; but when attached, have a fixed relation with respect to each other. The sling is formed of a flexible strap preferably of woven webbing 13, and at one end is provided with a metal clip 14, to which a grip frame 15, is pivotally connected. This grip frame in the present instance is provided with three cross-bars 16, 17 and 18 respectively,—the clip 14, in this instance being pivotally attached to said bar 18. The other end of the sling strap or webbing is provided with a hook plate 19, and a spring tongue 20, to close the mouth of the hook,—it being observed that both the plate 19, and said tongue 20, are of substantially the same width as the sling strap or webbing in order that the end of the strap to which said hook plate and tongue are attached may be passed through either of the links 10 or 11, on the gun to enable the sling to be attached or detached while said plate and tongue are attached to the webbing-end. This is desirable, because it avoids the necessity of first threading the strap or webbing through the gun links and afterward riveting the plate and tongue, or the grip frame thereto, which would obviously be exceedingly inconvenient in replacing a worn or broken sling by a new one. It will also be noted that the hook plate and tongue have a width and thickness with respect to the width and length of the slots 21 and 22, of the grip frame, to permit them to pass through said slots and facilitate threading of the sling while said plate and tongue are attached thereto.

In attaching the sling to a gun that end of the strap to which the hook plate 19, and the tongue 20, are attached will first be passed, say from the outer side through the link 10, on the gun stock; said end is then drawn through the link 10, and carried to link 11, and passed through the latter link from the inner to the outer side; the hook plate and web attached thereto is next passed under bar 16, of the grip frame and out through slot 21; then around bar 17; back through slot 22, and then drawn toward and secured to the bar of the link 10, through which it was first passed. In securing the hook plate 19, to the link 10, through which it was first passed, it is passed thereunder from the outer side,—the tongue 20,

yielding to permit the engagement and then snapping in place again to secure the hook, in engagement with said first-named link. When the sling is thus attached, the thread-
5 ing thereof through the grip frame 15, will produce sufficient friction to prevent slipping, and to either tighten or loosen the strap it is only necessary to grasp the grip frame 15, and draw it, in this instance, to-
10 ward the barrel-end of the gun to effect a tightening, or draw it in a reverse direction to produce a loop as shown in Fig. 3, without disturbing the relative relation of the fixed links 10 or 11.

15 Obviously, the reason for providing the loop by elongating the strap between the fixed links is to enable the gun to be slung over the shoulder for conveniently carrying the same,—the adjustment of the strap being easily effected and without the use 20 of injurious buckle-tongues or pointed teeth that would scratch or cut the threads of the strap if the latter be formed of a woven webbing.

25 Having thus described my invention, what I claim is,—

1. The combination with a gun having two spaced-apart links attached thereto said links having a definite spaced relation with 30 respect to each other on the gun, of an imperforate strap having one end detachably secured to one of the spaced gun-links and threaded through both of said links to form at least two complete stretches between the 35 spaced links and means at the other end of

the strap for slidably engaging one of said stretches of the strap.

2. The combination with a gun having two definitely spaced-apart links thereon, of an imperforate strap provided at one end 40 with a coupling of a width and thickness to pass through said definitely spaced links, said coupling detachably engaging one of said links and the imperforate strap having at least two complete stretches between said 45 links, and means at the other end of said strap for slidably engaging one of said complete stretches of imperforate strap.

3. The combination with two definitely spaced-apart links, of an imperforate strap; 50 a slotted frame attached to one end of the imperforate strap; a coupling device attached to the other end of the strap,—said coupling device being of a width and thickness to enable it to pass through both links 55 and also to pass through the slots in said slotted frame and said coupling device detachably engaging one of said links, and the strap being threaded through the two definitely spaced links to provide at least two 60 stretches between the links, and the slotted frame frictionally engaging one of said stretches of the imperforate strap between the links.

In testimony whereof I affix my signature in presence of two witnesses.

JAMES P. HOOPER.
